DESIGN FOR A COOKING-STOVE.

Specification forming part of Design No. 6,306, dated December 17, 1872.

To all whom it may concern:

Be it known that we, NICHOLAS S. VEDDER, of the city of Troy, in the county of Rensselaer and State of New York, and TOBIAS S. HEISTER, of Lansingburg, in said county and State, have jointly invented and produced a new and original Design for Cook-Stoves, of which the following is a specification, reference being had to the accompanying wood cut or engraving of a stove which embodies our said design.

One part of our said invention consists of the compound ornament P, shaped and arranged on a door or panel of a stove, as shown in the aforesaid wood-engraving. Another part consists of the ornament or ornaments Q or Q', shaped and arranged on a door or doors or panel or panels of a stove, substantially as represented in the aforesaid cut. Another part consists of the combination of the compound molding R and ornament or ornaments P or Q on a door or doors or panel or panels of a stove, substantially as represented in the cut, with or without the bead ornamentation t. Anoth-

er part consists of the design for the bottom plate S, side plate T, hearth-plate U, and top plate V, in combination, as distinguished by the moldings W, in combination with the particular shape of, and moldings x y z upon, the side plate T, as shown in the aforesaid wood-cut.

What we claim as our invention is—

1. The ornament P, shaped and arranged as herein set forth.
2. The ornament or ornaments Q or Q', shaped and arranged as herein described.
3. The design for the combination of the molding or moldings R and ornament or ornaments Q or P, as herein set forth.
4. The design for the combined bottom side, hearth, and top plates S, T, U, and V, as herein described and shown.
